The FIGURE is a front view of a display screen with graphical user interface showing the new design.

The ornamental design which is claimed is shown in solid lines in the drawing. The outer two broken line rectangles in the drawing showing the display screen and the other even-dash broken lines showing portions of the graphical user interface are included for the purpose of illustrating portions of the article only and form no part of the claimed design. The dot-dash lines show the bounds of the claimed design and form no part thereof.
